ATTORNEY.

UNITED STATES PATENT OFFICE.

ERNST KALLMEYER, OF NEW YORK, N. Y.

SYRINGE HEAD.

Application filed February 2, 1924. Serial No. 690,135.

This invention relates to heads for syringes and has for its object to provide an improved head which will guide the water or other cleansing solution in such a manner in respect to the parts to be cleansed, that the water or solution will not injure the same.

Heretofore, an objection to syringe heads was that the fluid would energetically come in contact with the most delicate parts of the body, and the object of this invention is to remove such destructive features.

The invention will be more fully described hereinafter, shown in the drawings and finally pointed out in the claims.

In the accompanying drawings,

Fig. 1 is a longitudinal sectional view taken on line 1—1 of Fig. 2 of the uppermost or outermost end of my improved 20 syringe head;

Fig. 2 is an end view thereof;

Fig. 3 is an end view of another form embodying my invention;

Fig. 4 is a longitudinal section taken on 25 line 4—4 of Fig. 3.

Fig. 5 is a plan view of the form shown in Figs. 3 and 4, showing the general direction of the jets;

Fig. 6 is a perspective view of a head embodying my invention, showing the same applied to a particular form of nozzle;

Fig. 7 is a section taken on line 7—7 of Fig. 6; and

Fig. 8 is an enlarged perspective view of 35 the outer end of the head shown in Figs. 6 and 7.

Similar characters of reference indicate corresponding parts throughout the various views.

40 Referring to the drawings and more particularly to Fig. 6, there is shown a nozzle 10, which is provided with longitudinal ribs 11, with valleys 12 therebetween. These ribs 11, and valleys 12, taper from one end of the 45 nozzle portion to the tip thereof. Within the valley portions there are arranged openings 13, either with one opening for each valley or two or more, as desired. The tapered end of this nozzle forms the head 50 thereof and in this embodiment of the in-

vention is as also shown in Figs. 1 and 2, the end of the nozzle curved downwardly and inwardly. The peak 14 of the nozzle in the embodiment shown in Figs. 1 and 2 is a circumferential, rounded, portion. The 55 curved downward and inward depression which is indicated by 15, forms, with the body portion of the nozzle, a chamber 16, and in this embodiment this chamber is single, and extends circumferentially of the 60 nozzle. Laterally, inwardly, of this chamber 16, openings are provided which are indicated by 17, and these openings are formed in the walls of the member 15, so that the water or other solution is directed 65 inwardly perpendicularly to the axis of the nozzle. In the embodiment of Figs. 1 and 2, three openings are provided. The jets thereby formed mingle within the cavity 18 and gradually exude over the peak 14 and 70 thereby come in contact with the body and perform their cleansing function.

In the embodiment shown in Figs. 3 and 4, the chamber 16 is replaced by three communicating chambers 20 formed by the walls 75 of the head and intermediate of these chambers depending portions 23, which extend inwardly of the tip of the head, so as to form depressed portions between the walls forming the chamber 20. The walls forming the chamber 20 are provided at the curved inward portion thereof with openings 22 which cause the jets to be directed 80 inwardly toward the axis of the head. In the embodiment of Figs. 3 and 4, the three 85 chambers 20 are provided with jets that are formed and directed preferably, in each instance in a direction intermediate the two other chambers. This action of the jets is clearly shown in Fig. 5, in which each chamber 20 has its opening 22 and each jet of 90 each chamber 20 is directed between the other two chambers. By this arrangement the jets may be free to project and impinge upon the parts of the body instead of being 95 merged and intermingled, as is the case with Figs. 1 and 2. Instead of providing three such chambers with one opening each, a greater or less number of chambers can of course be provided and each chamber may 100

of course have one opening but in each case the opening is directed substantially perpendicular to the axis of the head. The openings can also be so arranged at an inclination of the walls forming the openings so that that the jets will pass each other without striking; this may be readily accomplished by a certain relativity of the inclinations of the respective walls forming the openings. The advantage of this form is that the jet may directly contact with the body without having any of its force lost as would be the case if the jets impinge upon each other.

15 The heads which have been described in connection with Figs. 1—5 are substantially the same as the part of the nozzle described in connection with Figs. 7 and 8, and in this case the walls of the nozzle forming 20 the ribs have such a contour that they form the walls of the chambers 20, while the walls forming the end of the valleys 12 form the depressed portions of the tip of the head and these depressed portions permit the jets to 25 pass so that the jets may impinge against the body with their full force without being diminished by striking any wall of the head or striking any of the jets themselves. In the embodiment shown in Fig. 6 the walls 30 of the nozzle are thus so arranged that the walls of the ribs 11 merge into the walls forming the chambers having the jet openings and the walls of the valleys form the intermediate portions depressed in respect to 35 the chambers 20.

As stated, one of the further important features of the invention is to have the walls of the jet openings arranged so as to be substantially perpendicular to the axis or 40 at least in such a way that the jets themselves do not project directly outwardly of the tip of the nozzle, along the axes thereof. The invention thus overcomes the use of devices which have their openings directed 45 against the most delicate and most likely to be injured parts of the body, the contact with which by foreign matter sometimes is a cause of death; whereas, the direction of the jets according to my improved invention 50 enables certain parts of the body to be directly impinged by the jets without their coming into contact with the more delicate parts just referred to.

The heads for syringes embodying my invention may be made either of glass or hard rubber or other suitable material well known to one skilled in the art. The manufacture thereof is inexpensive and the operation of the same is at all times under control. The 55 further advantage of my improved invention is that by the arrangement of the jets, should any of the water or solution be deflected towards the delicate part, they would have lost their pressure effect and so would 60 not be injurious.

I have described and shown various embodiments of my invention but I do not wish to be limited thereto since the invention may be embodied in various forms, the spirit of the invention being defined by the appended 70 claims.

I claim as new:

1. A head for syringes comprising: a chamber-forming elongated body-member of wave-like extending cross section so as to 75 form alternative ribs and channels on its outer circumference; in combination with an inwardly domed end wall having fluid outlet openings directed substantially perpendicularly to the axis of the body-member, so that the fluid jets do not strike directly against the epidermis but mingle within the cavity of the domed wall, to exude gradually over the crest of the domed part.

2. A head for syringes comprising: a chamber-forming elongated body-member of wave-like extending cross section so as to 80 form alternative ribs and channels on its outer circumference; in combination with an inwardly domed end wall having fluid outlet 85 openings directed substantially perpendicularly to the axis of the body-member, so that the fluid jets do not strike directly against the epidermis but mingle within the cavity 90 of the domed wall, to exude gradually over the crest of the domed part; and a crest part 95 between the outer circumferential wall and the inwardly domed end wall having alternating higher portions and depressed portions, so as to facilitate the outflow of the 100 fluid from the cavity of the domed end part into the channels of the circumferential part.

3. A head for syringes comprising: a chamber-forming elongated body-member of wave-like extending cross section; in combination with an inwardly domed end wall; and having fluid outlet openings in the inwardly receding parts of the longitudinal 105 grooves of the circumference; and having further in the said inwardly domed end wall fluid outlet openings, which are directed substantially toward the axis of the body member.

4. A head for syringes comprising a member having a plurality of chambers arranged circumferentially of the axis of the member and communicating with each other, each chamber having a jet opening, said opening being directed toward the axis of 115 the member, and the outer portions of said chambers extending beyond the portions of the member intermediate of the chambers.

5. A head for syringes comprising a longitudinal member having exterior rib and valley portions tapering toward the outer end thereof, said member having a chamber formed by extensions of the rib portions forming extended portions of the head of the member and each having an opening 120 125 130

therethrough directed toward the axis of the member, and said valley portions terminating in valley portions of the head of the member forming depressed portions in respect to the extended portions of the head of the member, said depressed portions being out of line with the openings in the ex-

tended portion permitting fluid to pass thereover without impingement with the walls thereof.

In testimony that I claim the foregoing as my invention, I have signed my name here-to.

ERNST KALLMEYER.
